US0D1073973S

(12) **United States Design Patent** (10) **Patent No.:** **US D1,073,973 S**
(45) **Date of Patent:** **** May 6, 2025**

(54) **ELECTROPORATION DEVICE**

(71) Applicants: **LIFE TECHNOLOGIES CORPORATION**, Carlsbad, CA (US); **Life Technologies Holdings PTE LTD**, Singapore (SG)

(72) Inventors: **Beng Heng Lim**, Singapore (SG); **Siu Wee Hon**, Singapore (SG); **Steven Huei Yeo**, Singapore (SG); **Joshua Mead**, San Diego, CA (US); **Roy Thompson**, Boston, MA (US); **Xin Mathers**, Poway, CA (US); **Victor Shapiro**, San Diego, CA (US)

(73) Assignee: **Life Technologies Holdings PTE Ltd**, **Life Tech**

(**) Term: **15 Years**

(21) Appl. No.: **29/841,776**

(22) Filed: **Jun. 8, 2022**

(57) **CLAIM**

The ornamental design for an electroporation device as shown and described.

DESCRIPTION

FIG. 1 is a front perspective view of an electroporation device, according to an embodiment;

FIG. 2 is a front view of FIG. 1;

FIG. 3 is a back view of FIG. 1;

FIG. 4 is a right side view of FIG. 1;

FIG. 5 is a left side view of FIG. 1;

FIG. 6 is a top view of FIG. 1;

FIG. 7 is a bottom view of FIG. 1;

FIG. 8 is a front perspective view of an electroporation device, according to an embodiment;

FIG. 9 is a front view of FIG. 8;

FIG. 10 is a back view of FIG. 8;

FIG. 11 is a right side view of FIG. 8;

FIG. 12 is a left side view of FIG. 8;

FIG. 13 is a top view of FIG. 8; and,

FIG. 14 is a bottom view of FIG. 8.
